VEHICLE LIFT GATE ASSEMBLY

Fortunato S. Ajero, Galion, Ohio

Application November 4, 1957, Serial No. 694,428

11 Claims. (Cl. 214—77)

This invention relates to vehicle tailgates; to a tailgate structure which may be employed as an elevator for vertically moving loads to and from the vehicle body; and more particularly this invention relates to a novel tail lift gate construction, including an improved operating mechanism therefor.

Tail lift gates for vehicles, such as trucks and trailers, have been known for some time. On the whole, however, the existing devices are far more complicated in relation to the work they perform than would seem to be necessary. In contrast, the present invention provides a highly simplified and efficient operating mechanism for tail lift gate assemblies, which mechanism may be readily provided, with or without the lift gate, as a packaged unit which may be readily mounted either to existing or new vehicles. The tail lift gate, of course, serves as a vehicle body closure, or it may be arranged as an elevator for raising or lowering loads to and from the vehicle body; and, the operating mechanism provides the actuating means whereby the gate is positioned upright as a closure or used as an elevator.

The primary object of this invention accordingly is to provide an improved lift gate operating mechanism, including means for moving the gate vertically or for moving the same to and from an upright position, utilizing the same power means to accomplish either of said movements.

Another object of this invention is to provide a tail lift gate operating mechanism characterized by its simplicity and economy of manufacture, and which may be readily mounted to new vehicles, or as an integral unit on existing vehicles without disturbing parts presently mounted thereon.

The foregoing and other objects, advantages and features of construction will become more apparent upon a consideration of the following description together with the accompanying drawings.

In the drawings:

Figure 1 is a more or less diagrammatic side elevational representation of the present invention, certain parts having been omitted for clarity, and showing the tailgate in lowered horizontal position;

Figure 2 is a view similar to that shown in Figure 1, but showing the tail lift gate in raised horizontal position;

Figure 3 is a view similar to that shown in Figures 1 and 2, showing the lift gate in upright closed position;

Figure 4 is a rear elevational view taken in the direction of the arrows 4—4 in Figure 1;

Figure 5 is a plan view taken on line 5—5 in Figure 4;

Figure 6 is a view taken on line 6—6 in Figure 4, showing a portion of the supporting members for the operating mechanism; and

Figure 7 is a schematic flow diagram of a hydraulic system which may be employed with the present invention.

Lift gates of the type herein described generally are found on vehicles such as trucks or trailers; although, in many instances they may be used for raising or lowering

2

loads to and from stationary means. Consequently, although the herein invention is described and illustrated as employed with a truck, it should be understood that this is done by way of example only and is not intended to limit the use of the present invention.

Reference is made first to the general environment in which the present lift gate mechanism may be used. Ordinarily, the mechanism will be used at the rear of a vehicle, and, as shown in the drawings, it usually is mounted upon the vehicle frame and below the vehicle body. When used as an elevator for carrying loads to and from a platform or the ground, the lift gate is held in horizontal position, as seen in Figure 1. When it is used to load or unload shipments to and from a vehicle body the lift gate is raised to a horizontal position such as that shown in Figure 2. In normally closed position, the lift gate is elevated and positioned upright to provide a closure for the vehicle body, as seen in Figure 3.

Only those portions of the vehicle incidental to the present invention are shown in the drawings, including chassis frame members 10—10, body cross-members 11, and frame members 12 supporting the latter and held on members 10. The vehicle body 13 includes a floor 14 and may or may not include side walls 15. The rear of the vehicle body generally is open adjacent the floor 14, to receive a lift gate 16, which when in elevated position provides an extension for the body floor 14, and when in upright position acts as a body closure member.

The lift gate operating mechanism generally is located symmetrically with reference to the lift gate 16 and the vehicle chassis to assure positive and balanced operation of the gate. In the illustrated embodiment of the invention the parts thus are arranged for symmetrical attachment to the vehicle, there being provided lift linkage and closure linkage for each end of the gate. However, an arrangement wherein the linkage is attached to the gate substantially around the center thereof also is within the contemplation of the invention. Since the illustrated embodiment of the invention discloses identical actuating linkage for each end of the lift gate 16, only the linkage for one end will be described, it being understood, of course, that the description is applicable to both ends.

Support for lift gate 16 is provided by a horizontal shaft 17 suitably supported at its outer end in a bearing 18 held in a bracket 19 supported by a cross member 20. Lift gate support further includes an arm or support link 21 keyed to shaft 17 adjacent one end thereof, and at its free or outer end the link 21 has a transverse extension 22 which is pivotally connected to an end frame member 23 of the lift gate 16, as shown in Figures 1 and 4 as a pivotal connection 24 adjacent to what may be referred to as the "hinged end" of the lift gate 16.

At its inner end shaft 17 is rotatably held in a support web 25 fixed to the vehicle frame. Conveniently, the web also may provide the support for cross member 20 as well as other hereinafter described parts of the invention.

Turning of shaft 17 is accomplished by a crank arm 26 fixed non-rotatably thereto and positioned adjacent a web 25. The crank arm 26 has a cam surface 27 engageable against a roller 28 rotatably held on a movable shaft 29. Shaft 29 is supported by a second roller 30 which rotatably travels in a track provided by a slot 31 in web 25.

A cross head 32 is pivotally mounted on shaft 29, and between paired webs 25—25, and is connected to a piston rod extension 33. The latter is connected to a piston 34 reciprocably movable within a cylinder 35 fixed to a support 36 extending between webs 25—25 and held thereby in a generally horizontal position. As piston rod extension 33 moves outwardly from cylinder 35 it carries the roller 28 on shaft 29 into engagement with the crank arm

cam surface 27, causing the crank arm 26 to turn and rotate its shaft 17. As shaft 17 rotates, its link arm 21 raises lift gate 16.

To assure that lift gate 16 is maintained horizontal as it travels from ground level to a position in the general plane of the vehicle body floor 14, a compression arm 37 is provided. Actually, arm 37 is a jointed arm comprising pivotally connected links or members 38 and 39, the latter of which is shorter and keyed to a shaft 40 for rotation therewith. The longer link 38 is pivotally connected with the hinged end of lift gate 16 at 41 and below pivotal connection 24.

Shaft 40 at its outer end is rotatably carried in a bearing 42 held in bracket 19, and at its other end is suitably rotatably supported by web 25. Rotation of shaft 40 is achieved by a crank arm 43 which is fixed thereto and carries a cam surface 44 also engageable by roller 28. As roller 28 moves outwardly from cylinder 35 it engages against cam surface 27 to cause shaft 17 to rotate counter-clockwise, as viewed in Figures 1 to 3, and raises link 21 and lift gate 16 thereby. In the meanwhile, the smaller link 39 of articulated arm 37 remains stationary while the longer link 38 pivots about the point 45 of arm articulation, which point, during raising of link 21, remains stationary while the outer end of link 38 follows the rising lift gate 16. During this time, articulated arm 37, and in particular link 38 thereof, is under compression as it maintains lift gate 16 in a horizontal position. The rotational thrust thus imparted by arms 38 and 39 to shaft 40 is imparted thereby to arm 43, resting against stop 47 (Figs. 1 and 2) which prevents backward rotation of shaft 40 during raising and lowering between the positions of Figs. 1 and 2.

The cam surface 27 of crank arm 26 further is so designed that at substantially the point where lift gate 16 reaches the level of the vehicle floor 14, further movement of roller 28 has no effect on crank arm 26, the cam surface 27 of which is then positioned contiguous and parallel with the path of roller 28.

As roller 28 continues its outward movement from cylinder 35, it next engages the cam surface 44 of crank arm 43. Further travel of roller 28 causes crank arm 43 and shaft 40 to turn clockwise, as viewed in Figures 1 to 3, thereby raising arm 37. Since this further outward movement of roller 28 has no effect on crank arm 27, the pivotal connection of link 21 to lift gate 16 remains stationary. Consequently, as link 37 rises, it causes lift gate 16 to pivot upwardly about its pivotal connection 24 and to an upright position, as best seen in Figure 3.

Roller 28, thus, in effect provides linearly positionable structure which acts as an "actuator" arranged to operate crank arms 26 and 43. As seen in Figure 1, the actuator roller 28 is engageable with crank arm 26 upon piston rod extension 33 moving outwardly from cylinder 35. As seen in Figure 2, roller 28 is engageable with crank arm 43, upon rod extension moving in the same direction. And in Figure 3, actuator roller 28 is shown at the limit of its travel, wherat it is positioned against crank arm 43 to hold gate 16 in vertical position while crank arm 26 rests atop roller 28 to maintain or latch the gate in elevated position.

As mentioned hereinbefore, the mechanism for each end of lift gate 16 is identical. As a result, two webs 25, two shafts 17, and two shafts 40 are provided. The shafts 17, 17, are arranged in axial alignment, as are the shafts 40, 40. However, shaft 29 extends through both webs 25 to carry rollers 28, 28, which actuate the respective crank arms 26, 26, and 43, 43, on the shafts 17, 17, and 40, 40.

The webs 25, 25, may be attached to the chassis frame members 10—10 by suitable means such as welding. As a result, the entire lift gate actuating mechanism may be applied to a vehicle as an integral assembly. In carrying this feature out, supporting cross member 20 is fixed to the webs 25, 25, and holds at each of its ends brackets 19,

19, which, together with the webs 25, 25, provide support for shafts 17, 17, and 40, 40.

Limiting stops 46 may be provided on the webs 25 for each of the crank arms 26, which stops assure positive stoppage of the rotation of the respective crank arms 26 adjacent thereto once lift gate 16 is raised to the position shown in Figures 2 and 3. Also, stops 47 may be provided on each web 25 to limit the movement of each crank arm 43 when lift gate 16 is in its lowered position, as seen in Figure 1.

As is apparent from the foregoing, each shaft 17, the crank 26 thereon, and the link 21 carried on the shaft, are fixed for common rotation together. Likewise, each shaft 40, its crank arm 43, and the respective links actuated thereby also are arranged together for common rotation.

Referring to Figures 1 and 7, the cylinder 35 has fluid reception ports 48, 49, at each end thereof, and fluid is carried thereto by respective lines 50, 51, connected to a common control valve 52 to which fluid is supplied by a line 53. By means of valve 52, together with a pump (not shown) fluid may be selectively supplied from a reservoir (also not shown) to either end of cylinder 35 to correspondingly move piston 34. By means of a suitable power take-off the pump may be driven by the vehicle motor.

Briefly, operation is as follows: With the lift gate 16 in lowered position, fluid is supplied to cylinder 35 through its port 48 to drive piston 34 to the right, as viewed in Figure 1. As each roller 28 is carried by piston rod extension 33 outwardly from the cylinder 35, it engages its respective cam surface 27 to rotate the shaft 17 and, cause link 21 to raise the lowered gate 16 until it is in the elevated position shown in Figure 2. The compression force then applied through pivot 42 to arm 38 by the weight of the gate and any load thereon is resisted by fixed stop 47 (Figs. 2 and 3) engaged by arm 43 and acting through shaft 40 to prevent arm 39 from turning. Once elevation of lift gate 16 ceases, each roller 28 becomes effective to cause rotation of a respective shaft 40, thereby causing the gate to move to the upright position shown in Figure 3.

To lower the lift gate 16, the reverse procedure is followed. That is, fluid is introduced into cylinder 35 through its port 49, thereby driving piston 34 to the left, as seen in Figure 1. As each roller 28 is carried towards cylinder 35, the weight of gate 16 causes it to rotate about pivot 24 as cam surface 44 bears against the moving roller 28, which action continues until arm 38 has moved endwise and caused arms 39 and 43 (fixed with shaft 40) to rotate back until arm 43 encounters its stop 47, when the horizontal position is reached. To assure positive rotation of gate 16 from its upright position, biasing means may be provided. In the illustrated embodiment of the invention, the biasing means is exemplified by a torsion spring 54 fixed about pivotal connection 41 and anchored between gate end member 23 and link 38 to urge lift gate 16 to rotate clockwise, as viewed in Figure 3.

As lift gate 16 is permitted to move down from its upper horizontal position, its weight causes shaft 17 to rotate clockwise as viewed in Figures 1 to 3, bringing the respective cam surfaces 27 to bear against the retarding rollers 28 until the gate reaches its lowered position as viewed in Figure 1.

It should be understood that each of the cylinder ports 48, 49, is provided with a suitable check valve mechanism, together with means which permits bleeding off of fluid through one cylinder port while fluid is supplied through the other port, as will be apparent to those skilled in the art.

An essential feature of the present invention is that no elaborate latch mechanism need be provided in order to maintain lift gate 16 in the elevated position shown in Figures 2 and 3, even when the gate is carrying heavy loads. This is accomplished by a unique cooperation

between the rollers 28, 28, and the respective cam surfaces 27, 27, they engage. Specifically, each crank arm 26 is so designed that when lift gate 16 is in its elevated position, its respective cam surface 27 contiguous with a roller 28 lies parallel with the path of said roller. As a consequence, not only does the roller 28 become ineffective as far as turning the crank 27, but the load on the arm 27 transmitted from gate 16 through link 21 is applied radially onto the roller 28, or normal to the surface thereof. No component of the load is applied as a turning force. The roller 28 thus effectively acts as a latch which maintains lift gate 16 elevated. Further, even after the roller 28 travels outwardly from cylinder 35, the cam surface 27 extends sufficiently far to lie parallel with the path of its additional travel, and continues to brought to bear on the roller 28. Thus, even after lift gate 16 is moved to upright position, roller 28 acts as a latch which maintains it in elevated position.

Another feature of the invention is that the entire cross-sectional area of cylinder piston 34 is utilized effectively when raising this gate 16. Put another way, the full diameter of piston 34 is available to receive hydraulic pressure when it is desired to raise lift gate 16. For any given size of elevating mechanism, this reduces the size of the cylinder necessary to lift a given load.

Still another feature of this invention is that the cylinder 35 is mounted stationary. No loads are brought to bear directly upon the cylinder or its piston rod, but instead the loads are borne by the rollers 28, 28, which travel in a horizontal path as piston 34 is actuated.

As is apparent from the foregoing description, the same direction of piston 34 movement which raises the gate to the position shown in Figure 2 also closes the gate to its upright position as shown in Figure 3. Consequently, the same setting of valve 52 which directs fluid through line 50 to move piston 34 to the right, as viewed in Figure 1, also is used when elevating the lift gate 16 to its upright position shown in Figure 3. Thus, the entire movement of the gate from its lowered position to its upright closed position, may be accomplished with a single valve setting. Consequently, the lift gate control mechanism, and in particular valve 52, may be greatly simplified.

It may be desirable to provide some form of holding means to maintain the lift gate in its upright position. Such means generally take the form of chains which hook the gate to the vehicle body. These holding means, of course, form no part of the present invention which involves raising and lowering the gate as a platform, or moving it to and from a closure position. However, when held in elevated position, the herein described links 38, 39, do provide means by which the gate may be maintained upright.

Although what has been shown and described is a preferred embodiment of the invention, it is to be understood that the herein disclosure is not intended to be exhaustive nor limiting the invention, but instead is given for the purpose of illustration so that the invention may be better understood.

Various changes and rearrangements of the details shown and described may be made without departing from the spirit of the invention, the scope of which is defined in the appended claims.

What is claimed is:

1. Apparatus comprising: a generally flat member; linkage for supporting said member including a lift arm pivotally attached with said member at one end, and link means connected with said member and arranged with said lift arm for cooperation therewith to maintain said member substantially horizontal during vertical movement thereof; a crank arm; means whereby said crank arm is arranged to rotate said lift arm; linkage actuating means including movable means arranged to turn said crank arm, further means arranged for guiding said

movable means along a predetermined substantially linear path, power means connected with said linearly movable means for driving the same in either direction along said predetermined path, whereby upon movement of said linearly movable means in a first direction, said member moves towards a lowered position, and movement of said linearly movable means in an opposed direction moves said member towards a predetermined elevated position, said crank arm including means adapted to ride atop said linearly movable means and out of the path thereof upon said member reaching said predetermined elevated position, whereby said member is assuredly maintained in elevated position.

2. Apparatus for providing a vehicle combination elevator and tail gate assembly, comprising: a generally flat member; linkage for supporting said member including at least one lift arm pivotally attached with said member at one end and at its other end mounted for rotation about a fixed point; link means arranged with said lift arm for cooperation therewith to maintain said member substantially horizontal during vertical movement thereof; lift arm actuating means for effecting vertical movement of said member in horizontal condition and including means operatively connected with said lift arm for applying torque thereto; hydraulic actuated power means for operating the latter means, including a stationary mounted cylinder, a piston and rod therein, structure connected with said rod and operative on said latter means, and means for guiding said structure along a substantially linear path, whereby movement of said structure in a first direction correspondingly elevates said member in horizontal condition towards a predetermined position, and movement of said structure in an opposed direction correspondingly effects movement of said member in horizontal condition towards a lowered position; and a crank arm connected with said link means, interposed in the path of said structure and engageable thereby, upon said structure moving in said first direction and said member reaching said predetermined position, to actuate said link means, the effective length of said link means being such as to cause swinging of said member to vertical closure position, said latter means including a second crank arm having a cam surface interposed in the path of said structure and against which the same bears as said member moves between said positions, said cam surface being positionable contiguous with said path and still engageable with said structure during movement of said structure against said crank arm to maintain said member assuredly at said predetermined elevated position.

3. Apparatus for providing a combination elevator and tail gate assembly for a vehicle, comprising: a gate member; lift arms symmetrically arranged with respect to said gate member for pivotal attachment thereto at one of their respective ends; each lift arm being mounted at its other end to a shaft for rotation about a fixed point; link means pivotally attached to said gate member and cooperable with said lift arms to maintain said gate member horizontal during vertical movement thereof; a crank arm operatively associated with at least one of said lift arms to effect turning thereof; an actuating member arranged for operative engagement with said crank arm; means for guiding said actuating member along a substantially linear path; power means for moving said actuating member in either of opposed directions along said path, whereby movement of said actuating member in one direction raises said gate member towards a predetermined elevated position and movement of said actuating member in the opposed direction effectively moves said gate member towards a lowered position; and a second crank arm positioned for engagement by said actuating member upon said gate member attaining said elevated position and said actuating member moving further in said one direction, said second crank arm being operatively associated with said link

means to effect operation thereof and pivoting of said gate member about its pivotal connections with said lift arms, said further movement of said actuating member having no effect on said lift arms, said crank arm including a surface interposed in the path of said actuating member during vertical movement of said gate member between said positions, arranged to lie substantially parallel with the path of said actuating member during said further movement thereof, but adapted to continue to bear against said actuating member to assuredly maintain said gate member elevated.

4. Load-unload apparatus for mounting on a road vehicle, comprising an elevator and means for raising and lowering it between lowered and raised positions wherein it is in load-unload cooperative association respectively with the roadway and with the body of the vehicle, the raising and lowering means comprising mutually engaging drive and driven members and means for guiding each for forward and return movement along a path which intersects the path of the other, means linking the driven member to the elevator to bring the elevator from lowered to raised position responsive to the forward movement of the driven member and to return the elevator from raised to lowered position responsive to the return movement of the driven member, power means for moving the drive member in its forward and return movements to cause the driven member to execute its said movements to raise and lower the elevator, and camming means contained in the driving and driven members and in their guiding means for maintaining driving engagement during the said elevator movement, the camming means moving the driven member substantially out of the path of the drive member as the elevator reaches its said raised position, the camming means then delivering the thrust of the raised elevator through the driven member to the drive member generally at right angles to the portion of the drive-member path the drive member then occupies.

5. Load-unload apparatus according to claim 4, wherein, upon the said elevator being brought into its said raised position, the said camming means maintains a holding engagement between the said members which locks the elevator in raised position in the absence of a return power thrust on the drive member by the said power means.

6. Load-unload apparatus according to claim 4, wherein the said path of the said drive member has a forward section which extends forwardly beyond the position occupied by the drive means when the said elevator has reached its said raised position, the said camming means maintaining a holding engagement between the said members, while the drive means is within the forward section of its path, which locks the elevator in raised position in the absence of a return power thrust on the drive member by the said power means.

7. Load-unload apparatus according to claim 4, wherein the said path of the said drive member is along a straight line, whereby a straight-line piston-cylinder couple may comprise the said power means.

8. Load-unload apparatus according to claim 7, wherein the said path of the said driven member is along the circumference of a circle along a chord of which the said path of the said drive member extends, the said driven member having the form of a lever arm pivoted at the center of the circle and extending into the path of the driven member.

9. Load-unload apparatus according to claim 4, wherein the said elevator is a gate-like structure which is horizontally disposed in and between its said lowered and raised positions and is pivotally supported by the said linking means along the side of elevator closest to the vehicle, the said driven member comprising the first of

two driven members each mutually engageable with the said drive member, the said path of the said drive member having an extension lying forwardly of the position occupied by the drive member when the rising elevator reaches raised position, means for guiding the second driven member for forward and return movement along a path which coincides with the forward extension of the path of the drive member, stop means limiting the return movement of the second driven member, second linking means linking the second driven member to the elevator to maintain the second driven member at the limit of its return movement and to support the elevator horizontally in and between its lowered and raised positions, movement of the drive means forwardly through the forward extension of its path after the elevator has been brought to its raised position maintaining holding engagement with the first driven means through the said camming means and effecting operating engagement with the second driven member to move it forwardly along its path to tilt the elevator from horizontal to vertical position through the second linking means.

10. Apparatus for positioning a road-vehicle tail gate which serves also as a load-unload elevator platform between an upright closure position with respect to the vehicle body, an upper horizontal position in cooperative load-unload association with the vehicle body, and a lower horizontal position in cooperative load-unload association with the roadway, comprising a driven reciprocal lift controller and a driven reciprocal tilt controller, a drive link linking the lift controller to the tail gate to raise and lower it responsive to forward and reverse movement of the lift controller, a tilt-link linking the tilt controller to the tail gate to tilt it between its upper horizontal and its upright positions responsive to forward and reverse movement of the tilt controller, a drive member and power means for moving it forwardly and reversely along a path wherein it operatively engages the driven controllers in succession, forward movement of the drive member first engaging and moving the lift controller forwardly to lift the gate from its lower to its upper horizontal position, the drive member, during its further forward movement, maintaining holding engagement with the lift controller to hold the gate lifted and also engaging and moving the tilt controller forwardly to tilt the gate from its upper horizontal position into its upright closure position, movement of the drive member in its reverse direction first acting through the tilt controller to tilt the gate from its upright position into its upper horizontal position while maintaining the said holding engagement with the lift controller, continuation of the reverse movement of the drive member acting through the lift controller to lower the gate from its upper to its lower horizontal position.

11. Apparatus according to claim 10, wherein the said tilt link serves also to support the gate against tilting from its horizontal position when the gate is below and is in its upper horizontal position, stop means coacting with the tilt link to maintain the gate horizontal when the said drive member is out of engagement with the said tilt controller.
